24/30; H02G 3/12; H02G 3/14; H01HFIG. 1 is a front view of the socket, showing my new design.
FIG. 2 is a back view thereof.

FIG. 3 is a bottom view thereof.

FIG. 4 is a top view thereof.

FIG. 5 is a left side elevational view thereof.

FIG. 6 is a right side elevational view thereof.

FIG. 7 is a front perspective view thereof; and,

FIG. 8 is a back perspective view thereof.

The masked areas adjacent to the dash-dot broken lines in the drawings depict portions of the socket that form no part of the claimed design. The dash-dot broken lines define the bounds of the claimed design and form no part thereof.

(Continued)

The masked areas adjacent to the broken lines in the drawings form no part of the claimed design. The dash-dot broken lines define the bounds of the claimed design and form no part thereof.
